CLAIM

I claim the ornamental design for a coax voltage surge protection ring, as shown and described.

DESCRIPTION

FIG. 1 is a top perspective view of a coax voltage surge protection ring with two pins;

FIG. 2 is top view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a bottom view thereof;

FIG. 8 is a top perspective view of a second embodiment of coax voltage surge protection ring with three pins;

FIG. 9 is top view thereof;

FIG. 10 is a front elevational view thereof;

FIG. 11 is a rear elevational view thereof;

FIG. 12 is a left side elevational view thereof;

FIG. 13 is a right side elevational view thereof;

FIG. 14 is a bottom view thereof;

FIG. 15 is a top perspective view of a third embodiment of coax voltage surge protection ring with multiple pins;

FIG. 16 is top view thereof;

FIG. 17 is a front elevational view thereof;

FIG. 18 is a rear elevational view thereof;

FIG. 19 is a left side elevational view thereof;

FIG. 20 is a right side elevational view thereof; and,

FIG. 21 is a bottom view thereof.
